EDWIN E. CARLSON AND LAWRENCE A. STEAD, OF CHESTER, PENNSYLVANIA.

WARP-DYEING MACHINE.

Application filed July 15, 1926. Serial No. 122,526.

Our invention relates to machines for dyeing yarn and particularly to the manner of supporting the yarn.

In the art of dyeing, the yarn to be dyed is passed in groups, called warps, through a dye bath and thus dyed. It is a well known fact that the dye liquor becomes exhausted of its coloring matter as the warps pass through the bath. This exhaustion is effected by the affinity of the coloring matter for the warp being dyed. An exhausted dye bath retains only a small percentage of its original coloring matter and this amount makes the bath a noticeably lighter shade.

Due to this exhausted condition in dye baths, it is a difficult problem to dye warps a uniform shade. The results obtained by the present dyeing machines are that the end of the warp dyed first is of the proper shade and the end of the warp dyed last is of a noticeably lighter shade.

Dyed yarn of non-uniform shade, when worked into a fabric, especially knitted goods, causes streaks in the fabric that is the chief cause of many second grade products.

An object of our invention is to provide a machine whereby warps of practically any length may be dyed a uniform shade.

Another object is to provide means for removing the supports from contact with the yarn at certain periods so that the dye liquor may more readily and evenly impregnate the yarn.

The drawings illustrate an embodiment of the invention and the views therein are as follows:—

Figure 1 is a plan view of a dyeing machine showing an embodiment of our invention.

Figure 2 a section on line 2—2 of Figure 1, showing the vat filled with dye liquor.

Figure 3 an enlarged section on line 3—3 of Figure 2, the warp and liquor being omitted.

Figure 4 a section on line 4—4 of Figure 3, drawn on a smaller scale,

Figure 5 a plan view partly in section of elements which form a part of our invention.

Figure 6 a side view partly in section of the elements shown in Figure 5,

Figure 7 an end view of the elements shown in Figure 6 looking from the right, and

Figure 8 a side view of a spacing bar which forms a part of our invention.

Referring to the drawings, 1 indicates a

vat adapted to contain a dye bath and 2 a reel rotatable on the vat, partly immersed in the bath and adapted to carry spaced layers of wound material through the dye bath.

The vat comprises end members 3 and a semi-cylindrical trough 4. The edges of the trough fit in opposed semi-circular grooves 5 in end members 3 and are clamped in the grooves by tie rods 6 which connect the end members. The vat thus formed may be lined with suitable non-corroding metallic lining 7 which would have no chemical effect on the dye bath. Each end member 3 is provided with a recess 8 and a pair of guides 9 extending upwardly from and aligned with the recess. These guides are adapted to guide the bearings of the reel into the recesses when removing or replacing the reel.

The reel has a shaft 10 and end flanges 11 secured to the shaft a short distance from its ends to provide trunnions 12 on which bearing blocks 13 are rotatably mounted. These bearing blocks rest in recesses 8 and have their outer ends extending out of the recesses so that hooks or other means of connection may be applied for raising the reel out of the vat.

The warp to be dyed is wound in spaced layers on bars 14 which are arranged in concentric series. The warp is first wound on the innermost series of bars, then on the next outer series and then on the third series and so on until a layer of warp is wound on each series of bars. To enable such winding, the bars are removably mounted in flanges 11 of the reel. This mounting consists of bar supports 15, each having a groove 16 closed at its inner end 17 and open at its outer end 18; and blocks 19 on the ends of each bar 14 which fit in the groove and abut each other as shown in Figures 2 and 5. The blocks are held in the grooves by notches 20 in which the corners 21 of the blocks engage. To cause the corners of the blocks to engage in the notches, the end faces 22 are cut so as to cause the block to tilt to one side. The end faces so cut make a block the shape of a rhomboid as shown in Figure 5. When the blocks abut each other in the groove, the upper block keeps the next lower block in position and its corner in the notch. The uppermost block is held in position with its corner in the notch by a latch 23 pivoted to one side of the support and held in closed position by a spring 24 at the other side of the support. This latch

closes the outer end 18 of the groove and thus prevents the bars 14 from being accidentally displaced.

- As the reel is rotated to pass the warp, 5 wound on its bars, through the dye bath, the bars are moved a short distance from the warp when immersed to the lowermost position in the bath to allow the dye liquor to thoroughly penetrate the warp. This is effected by mounting supports 15 in guideways 25 to slide radially of the reel. Each support 15 is held in its guideway by a plate 26 secured to the back of the support and disposed at the outer side of the reel flange. 10
- 15 Supports 15 at each end of the reel have cam followers 27 which travel in a concentric groove 28 in a cam plate 29. The cam plate at each end of the reel is fixed with bearing block 13 and is thereby held against rotation. 15
- 20 As the reel rotates and moves followers 27 in the groove 28, the followers when passing over the cam 30 at the lowermost part of the groove, will be raised to move supports 15 and bars 14 from the warp toward the center 25 of the reel. This allows the dye liquor to thoroughly penetrate those strands of the warp which were in contact with the bars.

Movement for rotating the reel is transmitted to gear teeth 31 on the periphery of flanges 11, from pinions 32 fixed on a drive shaft 33 rotatable in bearings 34 mounted on the upper edge of end members 3 of the vat. The drive shaft may be driven by any suitable driving means having a variable speed so 35 that it may be varied for dyeing different materials with different dyes.

In winding the warp on the reel, spacing bars 14 are all removed except one bar of the innermost series. The end of the warp is 40 then tied or otherwise fastened to this bar. The other bars of this series are slipped into grooves 16 one by one as the reel is turned and each bar is held in position, with the corners 45 11 of its blocks in notches 20, by the warp wound thereon. The reel is turned until a layer of the warp is wound on the full length 50 of the series of bars. Another series of bars is then slipped into the grooves of supports 15 and a layer of warp is wound on that series in a similar manner. A third series of bars is 55 then likewise slipped into the grooves of supports 15 and a layer of warp is wound thereon and so on with the other series of bars until a layer is wound on each series, after which the end of the warp is tied to one of the bars of the outermost series. The reel is then raised 60 and moved from its place of winding and lowered into the vat with its bearing blocks 13 sliding between guides 9 until they come to rest in recesses 8 in end members 1. As the reel is lowered into the vat, gear teeth 31, on the peripheries of reel flanges 11, will come into mesh with pinions 32. The reel is then rotated at the proper speed by drive shaft 33. 65 During rotation the layers of warp pass

through the dye bath in the vat and constantly churn the same, thus keeping the bath thoroughly mixed and of uniform shade throughout. As bars 14 pass the lowermost position in the vat, cam 30 in each groove, 70 and its associated parts, will cause the bars to be moved upwardly from the warp to allow the dye liquor to penetrate the warp contacting with the bars. After this point is passed the bars are returned to their original position to keep the warp tightly on the reel. At the end of the dyeing period, the dye bath will become partly exhausted of its coloring matter which makes the bath of a lighter shade. The effect of the lighter shade dye 75 liquor being the same on the entire warp, the entire warp will be dyed a uniform shade. The reel is then raised by suitable raising mechanism, which is connected to the overhanging ends of the bearing blocks 13, and 80 removed from the dye bath and lowered to a place for unwinding the warp from the reel. In unwinding, the steps for winding are retraced; it being understood that, if desired, a dyed warp may be unwound from one reel 85 and an undyed warp wound on a second reel 90 while a warp is being dyed on a third reel.

Of course the dyeing machine illustrated is susceptible of various modifications and changes without departing from the invention herein disclosed and hereafter claimed. 95

We claim:—

1. A dyeing machine including a vat; a reel mounted in the vat; bar supports mounted for inward movement on the ends of the reel; spaced bars carried by the supports, upon which material to be dyed may be wound in concentric layers, and means for rotating the reel. 100

2. A dyeing machine including a vat; a reel mounted in the vat; bar supports mounted for inward movement on the ends of the reel; bars removably mounted in the supports, upon which material to be dyed may be wound in concentric layers, and means for 105 rotating the reel. 110

3. A dyeing machine including a vat; a reel mounted in the vat; bar supports slidable on the ends of the reel; bars mounted on the supports; means fixed with the vat for sliding 115 the supports, and means for rotating the reel.

4. A dyeing machine including a vat; a reel mounted in the vat; bar supports slidable on the ends of the reel; a cam follower on each support; cams fixed with the vat and co-acting with the followers to slide the supports, and means for rotating the reel. 120

5. A dyeing machine including a vat; a reel; bar supports slidable on the ends of the reel; bars mounted on the supports; a cam follower on each support; trunnions on the reel; bearing blocks on the trunnions mounted on the vat; cams fixed with the bearing blocks and co-acting with the followers to slide the supports, and means for rotating the reel. 125 130

6. A dyeing machine including a vat; a reel mounted in the vat; bar supports mounted for inward movement on the ends of the reel, each having a groove closed at one end and notches in the side walls of the groove; bars; means on the end of the bars fitting in the grooves and adapted to engage in the notches to hold the bars in position; means on the supports for closing the opposite end of the grooves to lock said means in position, and means for rotating the reel.

7. A dyeing machine including a vat; a reel mounted in the vat; bar supports mounted for inward movement on the ends of the reel, each having a groove closed at one end and notches in the side walls of the groove; bars; angular blocks on the ends of the bars fitting in the grooves and engaging in the notches; means on the supports for closing the open end of the groove to lock the blocks in position, and means for rotating the reel.

8. A dyeing machine including a vat; a reel mounted in the vat; bar supports mounted for inward movement on the ends of the reel, each having a groove closed at one end and notches in the side walls of the groove; bars; angular blocks on the ends of the bars fitting in the grooves and engaging in the notches; a latch pivoted on each support adapted to close the open end of the groove to lock the blocks therein, and means for rotating the reel.

9. In a dyeing machine, a reel including a shaft, flanges on the shaft, radially disposed rows of spacing bars extending between the flanges, and a cam for successively raising each row of spacing bars radially inward.

10. In a dyeing machine, a reel including a shaft, flanges on the shaft, radially disposed rows of spacing bars extending between the flanges, and means for moving the rows of spacing bars radially of the reel.

11. In a dyeing machine, a reel including a shaft, flanges on the shaft, radially disposed

rows of spacing bars extending between the flanges, and means for successively moving each row of spacing bars radially inward.

12. In a dyeing machine, a reel including a shaft, flanges on the shaft, radially disposed rows of spacing bars extending between the flanges, the corresponding bars in each row being equidistant from the shaft, and a cam for successively moving each row of spacing bars radially inward.

13. In a dyeing machine, a reel including a shaft, flanges fixed on the shaft and having radially disposed guideways, and spacing bars carried by opposed guideways, and arranged in concentric circles.

14. In a dyeing machine, a reel including a shaft, flanges fixed on the shaft and having radially disposed guideways, spacing bars slideable in opposed guideways and arranged in concentric circles, and a latch at each guideway for holding the bars against radially outward movement.

15. In a dyeing machine comprising a vat and a reel rotatable therein, radially disposed rows of yarn supporting bars on said reel, a stationary cam on said reel, and cam followers on each row of supporting bars adapted to successively engage said cam to move said supporting bars out of contact with said yarn.

16. In a dyeing machine comprising a vat and a reel rotatable therein, unitary rows of yarn supporting bars on said reel, a cam plate on said reel, a groove in said plate, a cam in said groove, and cam followers on each unitary row of yarn supporting bars operating in said groove and adapted to move said bars when engaged by said cam.

In testimony whereof we have signed our names to this specification.

EDWIN E. CARLSON.
LAWRENCE A. STEAD.
